Attnys.

UNITED STATES PATENT OFFICE

DANIEL O'HARA, OF PHILADELPHIA, PENNSYLVANIA, ASSIGNOR TO U. S. BOBBIN & SHUTTLE COMPANY, OF PROVIDENCE, RHODE ISLAND, A CORPORATION OF RHODE ISLAND

SHUTTLE EYE

Application filed December 30, 1927. Serial No. 243,590.

This invention pertains to weaving shuttles and more particularly to a shuttle eye of self-threading type. The self-threading or automatic type of shuttle is used very extensively in high speed automatic replenishing looms, and so long as soft yarns are used the usual form of eye is quite satisfactory, but when wiry yarns, for example rayon, hard twisted silk, or the like, are employed, difficulty is frequently experienced from the tendency of the yarn to unthread itself from the shuttle eye. This action is probably due to the fact that wiry yarns uncoil freely from the end of the bobbin, thus providing slack 10 yarn within the shuttle body or between the shuttle and the fell of the cloth, and when the shuttle stops abruptly at the end of its travel in either direction, the momentum of this slack wiry yarn is sometimes sufficient 20 to throw the yarn out of the shuttle eye, thus leaving the shuttle unthreaded and usually causing the yarn to break on the next pick.

In accordance with the present invention, I provide a shuttle eye of self-threading type, comprising thread guiding elements and other features usual to such shuttle eyes, but in addition having a guard device which effectively prevents the yarn from unthreading itself from the shuttle eye under the conditions above described, and which is equally effective to prevent the thread from escaping either in a forward or rearward direction from the eye. This guard does not interfere in the least with the usual functions of the eye or with the threading operation; it does not add substantially to the bulk of the shuttle eye or to its weight, and is so simple that the increase in cost of the shuttle eye is by reason of the provision of this guard is substantially negligible.

In the accompanying drawings I have disclosed one preferred embodiment of the invention by way of example, together with a slight modification thereof, but wish it to be understood that the broad principle of the invention is not necessarily limited to the specific embodiments here shown, and that its objects may doubtless be attained by equivalent means fully within the spirit of the invention.

In the drawings,

Fig. 1 is a plan view of the forward end of a weaving shuttle provided with my improved self-threading eye;

Fig. 2 is a fragmentary vertical section 55 substantially on the line 2—2 of Fig. 1;

Fig. 3 is a side elevation of the shuttle eye removed from the shuttle body and indicating the operation of my thread guard device when the shuttle stops at the end of its forward pick;

Fig. 4 is a view similar to Fig. 3 but showing the action of the guard device when the shuttle stops at the end of its rearward pick;

Fig. 5 is a rear end elevation of the shuttle 65 eye shown in Figs. 1 to 4 inclusive; and

Fig. 6 is a side elevation of a slightly modified form of shuttle eye.

Referring to the drawings, the numeral 1 designates the body portion of a weaving 70 shuttle of the usual type, such shuttle having the cavity 2 for the reception of the bobbin 3. For convenience in discussion, the end of the shuttle which contains the shuttle eye will hereinafter be referred to as the forward end of the shuttle, and this end of the shuttle is furnished with the usual cavity 4 for the reception of the shuttle eye 5.

This shuttle eye comprises a base member 6 having the longitudinally extending thread guiding channel or passage 7. An upright longitudinally extending wall member 8, preferably integral with the base 6, defines the right hand side of the groove or channel 7. This side wall 8 supports a top member 9, preferably integral with the wall 8, which overhangs the channel 7. At a point preferably intermediate its front and rear ends this overhanging flange-like top member 9 is provided with a depending guard member 10. This guard member is preferably integral with the top member 9 and extends downwardly substantially parallel to the wall 8. The member 10 is provided with a forwardly directed horn 11 and a rearwardly directed horn 12, such horns being curved and providing concave front and rear surfaces 13 and 14 respectively for engagement with the yarn as hereinafter described. The extremities of the horns 11 and 12 are spaced from

the outer edge of the base member 6 to provide a lateral entrance 15 to the thread passage 7, and preferably the extremities of the horns 11 and 12 are disposed to the right, as viewed in Fig. 5, of the vertical plane of the extreme outer edge of the base 6 to facilitate threading. For convenience in manufacture I prefer to make the guard member 10 of substantially fish-tail contour as illustrated in Figs. 2, 3 and 4, providing a notch N in its lower edge. The provision of this notch facilitates the shaping of the horns 11 and 12.

The thread eye is furnished with other usual features, for example yarn guiding posts, spurs, and the like, all of which are well known in the art and which need no discussion herein. The thread eye is secured in the cavity 4 in the forward part of the shuttle body in the usual manner. In threading the shuttle, the yarn Y is drawn forwardly from the mass M on the bobbin 3 and into the guiding groove 16 at the left hand side of the shuttle body. The yarn is now drawn forwardly into the notch 17 at the forward end of the shuttle body and drops down along the side of the guard member 10 and through the entrance opening 15 into the thread guide channel 7. The forward end of the yarn is then swung laterally beneath the spur 18 of the shuttle eye and into the transverse groove 19 of the shuttle body, and thence into the lateral delivery opening 20 of the shuttle.

At the termination of each forward pick of the shuttle there is a tendency for the yarn Y to slip off from the end of the bobbin by reason of its wiry character and its momentum, and this slack yarn tends to throw forwardly forming a loop 21 as shown in Fig. 23. Unless some means is provided to prevent it, this loop might easily escape through the entrance opening 15, and upon the next rearward pick would be drawn out of the shuttle eye, leaving the shuttle unthreaded. In the same way, at the termination of the rearward pick, the uncoiling or ballooning of the yarn at the end of the bobbin provides slack which tends to throw itself out of the shuttle eye in the form of a loop 22. By the provision of the guard member 10, having the concave yarn engaging surfaces 13 and 14, the escape of the yarn loop either in a forward or rearward direction is prevented and the shuttle remains threaded until replenishment is necessary.

In Fig. 6 I have shown a slight modification in which the shuttle eye 5^a is provided with a base member 6^a and the top member 9^a in the same way as that above described. In this arrangement, the guard member 10^a is provided with the concave front and rear surfaces above described, but its lower edge 23 is substantially straight and unprovided with a notch. This type of guard functions in substantially the same way as the guard

above described and effectually prevents escape of the thread from the shuttle eye, but I prefer the form disclosed in Figs. 1 to 4 inclusive, since it has certain advantages from the manufacturing standpoint.

While I have herein shown the guard device as integral with the shuttle body and as located in a definite position with respect to the front and rear ends of the shuttle eye, I wish it to be understood that the invention is not thus limited, but that the guard device may be made as an independent element, for example of wire suitably bent and attached to the body of the shuttle eye in any desired manner; that the guard may be placed in other positions as experience may direct, and that changes in proportions of parts may be made without departing from the spirit of the invention.

I claim:

1. A self-threading shuttle eye for weaving shuttles comprising a base having a longitudinal thread-guiding channel therein, a wall member at the inner side of said channel, a top member projecting from the upper part of said wall and overhanging the channel, and a guard depending from the outer edge of said top member, the lower edge of said guard being spaced from the base member to provide a freely open lateral entrance adapted to permit a substantially straight run of yarn to move laterally into the thread guide channel, the extreme front and rear edges of said guard being oppositely concave for preventing the yarn from throwing itself out through said lateral entrance in either a forward or rearward direction.

2. A self-threading shuttle eye for weaving shuttles comprising a base having a longitudinal thread-guiding channel therein, a wall member at the inner side of said channel, a top member projecting from the upper part of said wall and overhanging the channel, and a guard depending from the outer edge of said top member, the lower edge of said guard being spaced from the base member to provide a freely open and substantially unobstructed lateral entrance to the thread guide channel, said guard having concave front and rear faces arranged to face away from each other and adapted to catch the yarn if the latter is thrown rearwardly or forwardly respectively, by momentum, and thereby to prevent the yarn from escaping through the lateral entrance to the yarn guide channel.

3. A self-threading shuttle eye for weaving shuttles comprising a base having a longitudinal thread-guiding channel therein, a wall member at the inner side of said channel, a top member projecting from the upper part of said wall and overhanging the channel, and a guard depending from the outer edge of said top member, the lower edge of said guard being spaced from the base mem-

ber to provide a freely open and substantially unobstructed lateral entrance to the thread guide channel, said guard being of fish-tail contour, having concave front and rear edges for preventing yarn from escaping through

5 the lateral entrance.

4. A self-threading shuttle eye for weaving shuttles comprising a base having a longitudinal thread-guiding channel therein and also having a side delivery eye and a thread-leading slot leading from the side delivery eye to the longitudinal thread-guiding groove in the base, a wall member at the inner side of said channel, a top member projecting from the upper part of said wall and overhanging the channel, and a guard depending from the outer edge of said top member, the lower edge of said guard being spaced from the base member to provide a lateral entrance to the thread guide channel, said guard being provided with forwardly and rearwardly directed horns disposed rearwardly of the side delivery eye and in a plane inside of the outer edge of the yarn guide channel and extending away from each other.

5. A self-threading shuttle eye for weaving shuttles comprising a base having a longitudinal thread-guiding groove therein and also having a side delivery eye and a thread-leading slot leading from the side delivery eye to the longitudinal thread-guiding groove in the base, an upstanding longitudinal wall integral with the base at one side of the guide groove, a top member integral with said wall overhanging the guide groove, a guard integral with said top member depending from the outer edge of the latter at a point between the front and rear ends and rearwardly of the side delivery eye, said guard having forwardly and rearwardly directed horns extending away from each other and spaced from the base and terminating at points within and adjacent to the outer side of the thread-guiding groove.

45 Signed by me at Providence, Rhode Island, this twenty-eighth day of December, 1927.

DANIEL O'HARA.
